(57) **CLAIM**

The ornamental design for a CD tuner, spotlight and fluorescent lantern, as shown and described.

DESCRIPTION

FIG. 1 is a front view of the CD tuner, spotlight and fluorescent lantern showing my new design;

FIG. 2 is a rear view of the CD tuner, spotlight and fluorescent lantern of FIG. 1;

FIG. 3 is a left side view of the CD tuner, spotlight and fluorescent lantern of FIG. 1;

FIG. 4 is a right side view of the CD tuner, spotlight and fluorescent lantern of FIG. 1;

FIG. 5 is a top plan view of the CD tuner, spotlight and fluorescent lantern of FIG. 1;

FIG. 6 is a bottom plan view of the CD tuner, spotlight and fluorescent lantern of FIG. 1;

FIG. 7 is a front view, partly in broken lines, of the CD tuner, spotlight and fluorescent lantern of FIG. 1 and further illustrating that portions of a compartment and a lamp are rotatable; and,

FIG. 8 is a left side view, partly in broken lines, of the CD tuner, spotlight and fluorescent lantern of FIG. 1 and further illustrating that a portion of a compartment is rotatable.
